US0D1091475S

(12) **United States Design Patent** (10) Patent No.: **US D1,091,475 S**
(45) Date of Patent: ** Sep. 2, 2025

(54) **CONNECTOR PLUG**

(71) Applicant: **Dongguan Chogori Electric Technology Co., Ltd**, Dongguan (CN)
(72) Inventor: **Yuanze Wu**, Dongguan (CN)
(73) Assignee: **DONGGUAN CHOGORI ELECTRIC TECHNOLOGY CO., LTD**, Guangdong (CN)

(**) Term: **15 Years**

(21) Appl. No.: **29/903,387**

(22) Filed: **Sep. 22, 2023**

(30) **Foreign Application Priority Data**

Mar. 24, 2023 (CN) 202330148857.8

(57) **CLAIM**

The ornamental design for a connector plug, as shown and described.

DESCRIPTION

FIG. 1 is a front view of a connector plug showing my new design;

FIG. 2 is a rear view thereof;

FIG. 3 is a left side view thereof;

FIG. 4 is a right side view thereof;

FIG. 5 is a top side view thereof;

FIG. 6 is a bottom side view thereof;

FIG. 7 is a front perspective view thereof; and,

FIG. 8 is a rear perspective view thereof.

The broken lines in the drawings illustrate portions of the article that form no part of the claimed design.

1 Claim, 8 Drawing Sheets
